ABSTRACT OF THE DISCLOSURE

After the slotted front end of a sledge handle has been started in the passage through a sledge head, the head is held stationary while the front end of the handle is pushed through it and out of its front. The projecting front end of the handle then is removed. The front end of the remainder of the handle is pushed against a stationary blade to open the front end of the handle slot. The handle then is moved forward against a stationary wooden wedge to force the wedge into the slot. Finally, the handle is pushed forward against a stationary metal wedge to force the handle onto that wedge also.

The customary way of assembling a handle with the head of a sledge, maul or hammer is to pound the head onto the front end of the handle until the handle is tight in the passage through the head and projects from its front end. The projecting portion then is sawed off and a wooden wedge is hammered into the closed handle slot within the head. For additional security, a metal wedge then is hammered into the front end of the handle. Usually this assembling is done by hand, but there are machines for hammering the head and the wedges into place. Although the machines relieve a workman of some of the manual operations, they are not very efficient. Their production rate is low.

It is among the objects of this invention to provide a method and apparatus for securing handles in sledge heads, which can be automatic, which completes the job in considerably less than a minute and which makes the connection between the handle and the head exceptionally secure.

The preferred embodiment of the invention is illustrated in the accompanying drawings, in which:

FIG. 1 is a front view of the machine;

FIG. 2 is an enlarged plan view;

FIG. 3 is an enlarged fragmentary horizontal section taken on the line III—III of FIG. 1;

FIG. 4 is a side view;

FIGS. 5 and 6 are enlarged fragmentary vertical sections taken on the lines V—V and VI—VI, respectively, of FIG. 1;

FIGS. 7 to 10 are fragmentary front views of the upper part of the machine, illustrating its principal operations; and

FIG. 11 is an enlarged fragmentary front end view of an assembled sledge.

Referring to FIGS. 1 to 4 of the drawings, a machine frame is formed from a tubular vertical post 1, from the lower end of which a pair of forwardly diverging legs 2 extend. The top of the post supports a pair of forwardly diverging arms 3 that may be in the form of heavy tubes. Secured to the front end of each of these arms is a vertical plate, the two plates 4 and 5 being in the same vertical plane and spaced apart.

Near the bottom of the post there is a vertical plate 7 in a plane parallel to plates 4 and 5. This lower plate is supported by a section 8 of I-beam, the rear end of which

is welded to the post. Secured to the front of plate 7 is a vertical hydraulic cylinder 9 provided with a double acting piston connected to a piston rod 10 projecting from the upper end of the cylinder. The upper end of the rod is connected to the lower end of a heavy vertical channel 11 that opens forward. This channel is slidable vertically in guides 12 projecting from the frame post. The sides of the channel are provided with pairs of slots 13 (FIG. 1) at vertically spaced intervals. A block 14 with laterally projecting horizontal flanges that can fit in any pair of those slots fits in the channel for supporting the wooden handle 15 of a sledge. Preferably, the block is provided with a downwardly extending recess for receiving the lower end of the handle. When the handle is shorter, the block will be placed higher up in the channel.

Means are provided for securely holding the handle in the channel or handle support. A convenient way of doing this shown in FIG. 1 is to mount vertically spaced pads 17 in the channel along one side. Similar pads 18 are disposed at the opposite side of the channel, but they are attached to double acting pistons mounted in horizontal hydraulic cylinders 19 secured to the outside of the channel. When fluid pressure is supplied to the outer ends of these cylinders, the movable pads press the handle against 25 the stationary pads and together they hold it securely.

Secured to the front faces of the two upper plates 4 and 5 of the frame are heavy blocks 21 and 22. The upper parts of these two blocks are provided with aligned rectangular passages therethrough, in each of which a heavy bar 23 fits as shown in FIGS. 1, 5, and 6. The outer ends of the bars are provided with axial bores, at the outer ends of which nuts 24 are welded for receiving adjusting screws. The screws extend away from the bars and are rotatably mounted in vertical strips 26. The screws permit the bars to be adjusted toward and away from each other to form an anvil with a central opening. The inner ends of the bars are located close enough together so that a sledge head 27 raised against them will engage the bottoms of the bars, but they are far enough apart so that they do not overlie the vertical passage 28 through the head.

The slotted front end of the sledge handle is started in the head passage by a workman simply pushing it part way into the passage. Then the sledge is placed in supporting channel 11 and clamped there between the pads. Fluid pressure then is supplied to the lower end of cylinder 9 to cause the handle support to move forward toward the anvil. This raises the sledge until its head strikes the anvil and can move no further, but the handle continues to move a short distance further and is pushed up through the head passage and out of its upper or front end into the space between the anvil bars, as shown in FIG. 7. This projecting end of the handle then is removed by a saw or router 30 carried by and driven by an electric motor 31 supported on a slide 32 that has laterally projecting flanges slidably mounted in guideways 33 in the parallel forks of a horizontal plate 34 secured to the top of the post and the front plates 4 and 5. A hydraulic cylinder 35 is mounted behind the slide on plate 34 and its piston rod 36 is connected to the back of the slide for moving the motor forward and back. When it is moved forward, the router removes the projecting end of the handle. The sledge then is lowered to its lower position for a moment.

The bottom of block 21 has a horizontal rectangular passage through it, in which a bottom bar 38 is slidably mounted. This bar projects from the inner end of the block, but not far enough to interfere with the vertical movements of the sledge. The projecting inner end of the bar carries a downwardly directed tapered blade 39 that extends transversely across it. With the sledge in

its lower position after its handle has been pushed up through the head, the blade is moved inwardly into a position directly above the closed slot in the handle by means of a pneumatic cylinder 40 connected with the outer end of the bar. While the blade is in this inner operative position, the sledge is raised again to press the cut off upper end of the handle against the blade as shown in FIG. 8, which thereby forms a wedge-shaped groove at the upper end of the closed slot. Then the sledge is lowered again and the blade retracted. Cylinder 40 is operated through a solenoid valve 41 fed through a pipe 42 from a header 43 extending across the machine and supported by the front of post 1. The valve has a built-in delayed action so that the blade will not be retracted until after the sledge has been disengaged from it.

One of the blocks, preferably block 22, contains a horizontal lower passage in which a bar 45 is slidably mounted. The inner end of this bar projects from the block but normally does not extend into the path of movement of the sledge. The inner end of the bar is formed for temporarily supporting a wooden wedge 46 facing the handle support and extending across the bar. This can be done, as shown in FIG. 8, by providing the bar with downwardly converging bores 47 having reduced lower end portions and plugged upper ends. There are three bores, as indicated in FIG. 5. Two of them are side by side in parallel relation. Slidably mounted in these bores are headed pins 48 that normally project from the bottom of the bar for engaging the opposite sides of the wedge and holding it up against the bar. Upward movement of the pins is resisted by coil springs 49 in the bores.

After the upper end of the slot in the handle has been opened by blade 39, the bar carrying the wooden wedge is moved inwardly to position the wedge in line with the slot. The bar is moved by a pneumatic cylinder 51 controlled by a solenoid valve 52 connected by a pipe 53 with header 43. The sledge is then raised again until its head strikes the overlying bar 45 as shown in FIG. 9. The pins 448 are forced up into the bar by the handle. During this movement, the wedge is forced into the handle slot to wedge the handle tightly within the head. The sledge and bar then are retracted. The groove formed in the handle by blade 39 helps the wedge get started into the handle slot, but it may not be necessary in every case.

Opposite the bar just mentioned, another bar 55 may be slidably mounted in a horizontal recess in block 21. The inner end of this bar projects from the block but normally is out of the path of movement of the sledge. The bottom of the inner end of the bar carries a magnet 56 to which a metal wedge 57 can be attached. For best results, this wedge is a downwardly tapered ring. The bar is moved inwardly by a pneumatic cylinder 58, controlled by a solenoid valve 59, to align the wedge with the axis of the sledge handle. Then the sledge is raised for the last time until its head strikes bar 55. During this operation, the metal wedge is pressed into the handle and wooden wedge within the head, as shown in FIGS. 10 and 11. The sledge is then lowered, the gripping pads are released from its handle and the finished sledge is removed from the holder. The use of a metal wedge as well as a wooden wedge is not absolutely necessary in all cases, but the combination provides a more secure connection than a single wedge does.

After the wooden and metal wedges have been put in place in this machine and the sledge has been placed in its holder, the machine can be set in motion and cycled automatically to cause it to perform its various operations on the sledge. A complete cycle of the machine takes less than a minute, so it has a high rate of production. There is no hammering, but only straight pressure. The only manual operations required are the starting of a handle in a head, placing of the sledge in

its holder, pushing of a button to start the machine, and removing the finished sledge from the machine.

We claim:

1. A machine for securing the slotted front end of a wooden handle in a passage through a sledge head, comprising a normally retracted movable support for holding the handle with its front end started in the head passage, an anvil spaced in front of said support and having a central opening through it, the support being movable forward to press the sledge head against the anvil and to then push the front end of the handle through the head passage and out into said anvil opening, whereby the handle slot is closed, means for cutting off the projecting front end of the handle, means adjacent the anvil for detachably supporting a wooden wedge facing the handle support, means for moving the wooden wedge support into and out of the space between the anvil and the retracted sledge support, and means for reciprocating said handle support to first press the sledge head against said anvil and to subsequently force into the front end of the handle slot a wooden wedge carried by the wooden wedge support.
2. A machine according to claim 1, in which said handle support reciprocates vertically, said anvil is above that support, and said wedge support is reciprocated horizontally.
3. A machine according to claim 1, including means for moving said cutting off means back and forth across said anvil opening.
4. A machine according to claim 1, in which said handle support includes a vertical channel for receiving a sledge handle laterally, a base member in the channel for the handle to rest upon, and means movable inwardly from a side of the channel for pressing against the handle therein to clamp it in the channel.
5. A machine according to claim 4, in which said base member is a vertically adjustable block for handles of different lengths.
6. A machine according to claim 1, in which said wooden wedge support is provided with bores, pins slidably mounted in the bores and projecting therefrom in positions to hold a wooden wedge between them, and springs in the bores compressible by said pins when the pins are engaged by the front end of a sledge handle.
7. A machine according to claim 1, including means adjacent the anvil rigidly supporting a blade facing the handle support, and means for moving the blade support into and out of said space to position the blade for engagement by the front end of the handle to open the front end of the handle slot before the wooden wedge is inserted.
8. A machine according to claim 7, in which the means that move the blade support into and out of said space include means for delaying retraction of that support until after said handle support has retracted far enough to withdraw the handle from said blade.
9. A machine according to claim 1, including means adjacent the anvil for detachably supporting a metal wedge facing the handle support, and means for moving the metal wedge support into and out of said space to position the metal wedge for engagement by the front end of the handle for insertion therein after insertion of the wooden wedge.
10. A machine according to claim 9, in which said metal wedge support includes a magnet for holding a metal wedge against it.
11. The method of securing the slotted front end of a wooden handle in a sledge head having a handle-receiving passage through it, comprising starting the handle into said passage, then holding the head stationary while exerting forward pressure against the rear end of the handle to push the front end of the handle through the head passage and out in front of it and close the handle slot, removing the projecting front end of the handle, retracting the sledge, moving a wooden wedge into alignment with said slot, again exerting said pressure to move

the handle forward to force the wedge into the slot, and retracting the sledge.

12. The method recited in claim 11, including the steps of moving a blade into alignment with the closed handle slot before insertion of the wooden wedge, exerting said pressure to move the handle forward to cause the blade to open the front end of its slot for subsequent reception of the wooden wedge, and then retracting the sledge and then said blade.

13. The method recited in claim 11, including the steps of moving a metal wedge into a position in front of the handle after insertion of the wooden wedge, again exert-

ing said pressure to force the handle forward onto the metal wedge, and retracting the sledge.
